MEANS FOR PIVOTALLY SUPPORTING AND
BRACING IRONING BOARDS

Alpha Perry Lantz, Washington, D. C.

Application March 29, 1945, Serial No. 585,435

2 Claims. (Cl. 38—129)

1

This invention relates to improvements in ironing boards of the type adapted to be normally stored in upright or parallel relation to a wall, preferably within a cabinet or chamber associated with said wall, and, when in use, capable of being swung downwardly to a horizontal position, at approximately right angles to the wall, or parallel with the floor to dispose the ironing face of the board in convenient and operative position.

The object of the present invention is to provide improved means for pivotally mounting the ironing board in place and for supporting the same, from the pivot end thereof in a strong and firm manner whereby to eliminate the necessity for additional or outside supports located away from the wall and constituting corresponding obstructions, beneath the ironing board when projected away from the wall in ironing position.

In the general type of structures, such as that to which the instant improvements appertain, wherein leaf hinges between the wall and board have been resorted to in combination with a prop or leg located at an outer portion of the board, in an effort to provide a stable and durable structure, the leaf hinges referred to are inherently relatively weak and frail and the additional remote leg or prop is objectionable as being in the way of the knees of the operator or obstructing what should be a free open space beneath the board, through which garments might be properly disposed on the board for ironing, rendering it especially desirable that the board be supported from its inner or attached end only. However, this desirable improvement presents the difficulty of adequately pivoting and supporting the board so that it will be perfectly rigid or steady when in projected or operating position, it being remembered that manual ironing operations are usually under considerable pressure or strength derived from the operator who, at times, presents a requirement that the hinged end of the board must be given primary importance in the construction.

In view of the foregoing the invention comprises, in its preferred embodiment thereof, a special pivoting means, combined with the ironing board and to which it is attached in a strong reinforced manner, said pivoting means comprising stub axles adapted to move in a rotative manner in suitable bearings at opposite edges of the board, the stub axles and bearings being of large diameter (substantially greater than the thickness of the board, for example), and having abutting parts or stops located a substantial distance

2

radially outward from the axis of the stub axles whereby to afford adequate supporting means to resist any normal or substantial abnormal pressure exerted by the operator on the board incident to an ironing operation.

The preferred embodiment of the invention incorporates a plurality of cooperating stops, say a pair at each edge of the hinged end of the ironing board, to afford adequate insurance that the board will be rigidly supported from said pivoted end only and without other props or legs, for example, under all conditions of service.

The invention also comprises the provision of a simple and efficient means for latching the ironing board in outwardly swung or operative position, against being accidentally swung upwardly away from operative position, but readily releasable when the board is to be thrown upwardly on its pivot into approximate parallelism with the wall or cabinet, it being observed that the arrangement of the parts are such that when the board is out of use in such parallel position the friction between the parts of the pivots may be such as to hold the board in stored or inactive position.

Details and refinements of the structure constituting the preferred embodiment of the invention, referred to, will be readily understood from the accompanying drawings, wherein said embodiments are illustrated, and the following detailed description thereof.

In the drawings—

Figure 1 is a vertical sectional view through the lower portion of a cabinet or receiving compartment in or attached to an ordinary wall or the like, of a room, the ironing board being illustrated in section transversely through the board and its supporting means, the board occupying a position projecting forwardly and out of the cabinet as in ironing position.

Figure 2 is a detail plan view looking down on the ironing board and associated parts at the left of Figure 1 to make clear the latching means for retaining the board in horizontal or ironing position.

Figure 3 is a vertical sectional view on the line 3—3 of Figure 2 looking to the right.

Figure 4 is a sectional view on the line 4—4 of Figure 1 looking to the right.

Figure 5 is a sectional view on the line 5—5 of Figure 2 illustrating the latching mechanism for the board when projected away from the wall into ironing position.

Figure 6 is a vertical sectional view on the line 6—6 of Figure 1 illustrating the supplemental supporting or stop engagement for the pivoting members of the board.

Figure 7 is a detail elevation of one of the stub axles provided with the pair of distinct stop supports adapted to cooperate with the complementary parts on the side wall of the housing or cabinet.

Referring more specifically to the drawings, wherein 'like' reference characters refer to the same parts in the several views, A represents the floor or base of a compartment or equivalent container having side walls B defining a compartment or space C, for the reception of the ironing board D, the same being arranged to be swung upwardly into a position parallel with the back wall E and within the chamber or space C or into horizontal position to project from the compartment and be in position for ironing purposes. To afford a strong and efficient mounting for the ironing board, especially in its projected position, I mount the same on a pivoting or hinging means comprising a pair of stub pintles F of substantial diameter, connected by a transverse member or seat portion G in which the end of the ironing board D is firmly seated and rigidly secured by bolts or rivets H (of any suitable number) passed through the overlying portion of the board and its seat. The portions D and G are reinforced and strengthened by metal straps J folded to embrace and pass around the end portions of the ironing board D and seat portion G and bolted thereto as shown. The extensions of the straps or equivalent metal members J extend as far as desired outwardly towards the forward end of the ironing board.

The stub pintles F project into and frictionally engage bearing sleeves K, extending inwardly from cover plates L bolted to the end walls B, of the cabinet, as shown at M, and preferably fitted into recesses formed in the face of said end walls. Reduced ends N of the stub pintles fit into perforations in the plates L to assist in centering the pivotal structure, said reduced ends being of substantial length, and carrying oppositely disposed wings or flanges O, arranged so that in the rotative movement of which they will engage complementary stop lugs P, projecting inwardly from and integral with the outer portions of the cylindrical bearings K, with the inner portions of which latter the stub pintles F have their rotatable frictional bearing, as heretofore pointed out. The bolts or securing rivets M, that secure the cover plates L to the end walls of the cabinet, are further utilized to fasten reinforcing plates Q to the inner sides of the end walls of the cabinet, said plates being connected at their inner or rear edges with a continuation thereof, crossing the back wall of the cabinet as indicated at R, and screwed or bolted to the back wall E, as clearly seen in Fig. 3, whereby the end walls of the cabinet are tied together as well as the opposite bearing portions for the ironing board mounted in rigid operative relationship, the cross or connecting piece R being cut-out centrally as at S to dispense with unnecessary metal.

It will be understood that when the ironing board is swung on its pivots to the outward position thereof, ironing pressure will be resisted by the lug or stop engagements O—P, and while this will suffice in light operations, it is expedient that a stronger and more rigid means be afforded to support the board under greater pressures or heavier working conditions and where, as is here

intended, no props or legs be furnished for engagement with the projected or free portion of the board when in use. To this end heavy members T of approximately inverted S-outline are provided upon the stub pintles F and fixedly secured as by bolts or screws U to the plates Q, and therethrough to the end walls B if found desirable, the interior or operative engagement of the same with the stub pintles F being after the fashion of the engagement of the parts O—P at the ends of the said pintles heretofore described. Thus the interior of each of the members T has arcuate ways V on the interior thereof receiving the opposite wings or lugs W on the shaft F and in the opposite swinging movements of the ironing board contacting the stops X at the ends of the ways V. The stops will limit the swinging movements of the ironing board into and out of the cabinet, as will be obvious, and the fittings between the stub pintles and their bearings being relatively tight, will frictionally hold the board against accidental falling out of the cabinet, or movement save at the will and under the manipulation of the user.

When the board is swung outwardly to its horizontal or operating position, it may be desirable to temporarily latch the same in that position and for that purpose a detent in the form of a lateral projection Y, integral with the strap J is arranged and adapted to ride into and out of a spring keeper Z, comprising a pair of oppositely disposed arms having inwardly projecting bulges or shoulders adapted to spring apart on the entrance of the projection Y and overlie the same when seated, release of the latch being obtained by slight pressure in swinging the board upwardly on its hinges thereby withdrawing the projection Y from between the spring arms of the keeper, the latter yielding as will be clear, for the purpose.

It will be understood that modifications of this arrangement may well be resorted to without departing from the spirit of the invention.

I claim:

1. In combination with a cabinet having side walls, of means for securing and supporting an ironing board in said cabinet, comprising a pair of stub pintles at the side edges of the board, a bridge piece connecting the stub pintles having a seat in which an end of the board is secured, bearing members mounted in the side walls of the cabinet for rotatably receiving the stub pintles, reinforcing strap members positioned around the meeting portions of the board and bridge piece and extending along the upper and lower edges of the said board, one of said reinforcing strap members having a lateral keeper to be moved with the board, and a spring latch fixed to one of the side walls of the cabinet to be engaged by the keeper when the ironing board is swung to operative position.

2. The combination with a cabinet having end walls, of an ironing board mounted therein, and means for supporting the ironing board, comprising a pair of stub pintles of maximum diameter near their ends provided with reduced portions in which the ironing board fits and is secured, cylindrical bearings within said walls into which said portions of maximum diameter pass and are rotatably mounted, combined with co-acting stops at the extremities of the stub pintles and on said tubular bearing, said tubular bearing being associated with inner and outer plates on said walls securing the bearings in position, and the inner plates carrying additional stops corre-

lated with complemental stops on the stub pintles to insure adequate support for the ironing board under relatively heavy ironing pressures.
